WALTER H. NOURSE, OF PORTLAND, OREGON, ASSIGNOR TO ELECTRIC STEEL FOUNDRY COMPANY, OF PORTLAND, OREGON

COLD SHUT FOR STEEL CHAINS

Application filed March 12, 1930. Serial No. 435,220.

This invention relates generally to the making of cold shuts, and particularly to the making of same from manganese steel castings.

5 The main object of this invention is to provide a novel form of cold shut in the form of a manganese steel casting.

The second object is to permit the use of manganese steel in the construction of cold 10 shuts, thereby enabling same to resist wear in a marked degree as compared with cold shuts made of other materials.

These, and other objects, will become more apparent from the specification following as 15 illustrated in the accompanying drawings.

Before entering into an explanation of this device it will be understood that cold shuts have long been made of forgings but castings have not been employed for this purpose 20 since it was impractical to bend them cold, and manganese steel castings which were peculiarly shaped on account of their wear-resisting properties were not used, due to the fact that when heated for the purpose of 25 bending same the manganese becomes brittle and fails to service. In order to overcome these difficulties there is constructed a cold shut whose form makes it possible to construct same of manganese steel and whose 30 shape permits same to be bent sufficiently to close same without in any way injuring the material of which the cold shut is formed.

Figure 1 is a side elevation of the open 35 device. Figure 2 is an end elevation of Figure 1. Figure 3 is a side elevation of the closed device showing same joining parts of a chain. Figure 4 is a section taken along the line 4-4 in Figure 3. Figure 5 is a section taken along the line 5-5 in Figure 3. Figure 6 is a section taken along the line 6-6 in Figure 1.

Similar numbers of reference refer to similar parts throughout the several views.

40 Referring in detail to the drawings, there is shown a cold shut consisting of a link having one fixed side 10 terminating in one direction in a rounded end 11 which itself terminates in a somewhat elongated tapering shank 12 which extends outwardly from the end 11 normal to the side 10. The opposite extreme

of the side 10 merges into a rounded end 13 which itself merges into a second straight side 14 which is bendable with relation to the side 10, and when cast is not parallel thereto but diverges sufficiently to permit a chain link 55 15 to pass between the face 16 of the flattened end 17 and the face 18 of the shank 12. The end 17 is provided with an elongated perforation 19 which tapers to conform to the shank 12 and is provided with a countersink 60 20 on its outer face.

The cross section of the link sides 10 and 14 is preferable as shown in Figure 6 which provides the maximum strength from a given weight of steel casting of the longitudinal 65 shape required for this purpose.

It will be noted in Figure 3 that the side 14 has been moved to a position parallel with the side 10 and that the shank 12 now occupies the perforation 19 and that the face 18 projects to the position shown in dotted lines.

The operation of the device is as follows: It is first made of a special grade of steel casting which will permit bending when cold in the shape shown in Figure 1. Whatever objects are to be joined thereby are first connected to the cold shut which is then closed, preferably by placing same between the jaws of a vise and forcing the ends together, as shown in Figure 3, and completing the operation by setting the bend with the blows of a hammer and then flowing the projecting portion of the shank 12 into the countersink 20 by a peening operation.

It will be seen that by this construction 85 certain prevailing conditions are utilized to produce a cheap strong cold shut which will resist wear better than a forged cold shut.

It will also be observed that a manganese 90 steel casting can be employed for this purpose which provides the wear resisting quality to the cold shut, and that although this material is susceptible to considerable bending without injury it requires only a very 95 small bend in order to move the side 14 from an open position to a fully closed position, and this bend is so uniformly distributed around the curve of the end 13 as to make same almost negligible and without 100

measurably detracting from the ultimate strength of the parts involved.

As previously suggested, the use of cold shuts is of itself not new; I am therefore not claiming such devices broadly, but I do intend to cover all such forms and modifications thereof as fall fairly within the appended claims.

I claim:

- 10 1. A manganese steel cold shut consisting of a fixed side terminating in a pair of rounded ends, one of said ends having a laterally projecting shank formed thereon normal to said straight side and the other rounded end merging into a bendable straight side having a perforation formed therein adapted to receive said shank.
- 15 2. A manganese steel cold shut consisting of a pair of converging straight sides joined together by a rounded portion, one of said straight sides terminating in a rounded end having a laterally extending shank, the opposite straight side terminating in a perforated end adapted to engage said shank when said straight sides are moved to a parallel relationship.
- 20 3. A manganese steel cold shut consisting of a pair of converging straight sides having a somewhat rounded connecting portion, the end of one of said straight sides opposite said joining portion having a hook formed thereon terminating in a laterally projecting shank lying in the plane of said straight sides, the adjacent end of the opposite side having a perforation therein corresponding with said shank and adapted to receive same when said straight sides are moved into parallelism.

WALTER H. NOURSE.
